UNITED STATES PATENT OFFICE.

JÓZSEF JUHÁSZ, OF UNITY STATION, PENNSYLVANIA.

LOCK.

1,035,196.

Specification of Letters Patent. Patented Aug. 13, 1912.

Application filed April 6, 1912. Serial No. 688,983.

To all whom it may concern:

Be it known that I, JÓZSEF JUHÁSZ, a subject of the King of Hungary, residing at Unity Station, in the county of Allegheny and State of Pennsylvania, have invented certain new and useful Improvements in Locks, of which the following is a specification, reference being had therein to the accompanying drawing.

10. This invention relates to locks, and more particularly to a screw lock used in connection with a door having a knob actuated lock.

15. The primary object of my invention is to provide a lock of the above type that can be operated from either side of a door and locked upon the inside of the door whereby it cannot be operated upon the outside of the door.

20. A further object of this invention is to provide a screw lock consisting of comparatively few parts, inexpensive to manufacture and highly efficient for the purposes for which they are intended.

25. With the above and other objects in view, the invention resides in the novel construction, combination and arrangement of parts to be hereinafter specifically described and then claimed.

30. Reference will now be had to the drawing, wherein:—

Figure 1 is a front elevation of the lock, Fig. 2 is a longitudinal sectional view of the same, Figs. 3 and 4 are cross sectional views of the lock, and Fig. 5 is a perspective view of a detached strike plate.

Further describing my invention with reference to the drawings, wherein like numerals denote corresponding parts throughout: 35. 1 denotes a portion of a door having a recess 2 for a rectangular lock casing 3, said casing having a longitudinal partition 4 dividing the casing into a longitudinal latch compartment 5 and a longitudinal bolt compartment 6, the latter having transverse partitions 7, 8 and 9, also a bearing 10. The casing 3 is closed by a front plate 11 and extending through said front plate, casing and the door 1, also a face plate 12 carried by said door, is a knob spindle 13 provided with knobs 14. The spindle 13 extends through a hub 15 having a latch 16 and a projection 17. The projection 17 is engaged by a flat spring 18 arranged in the compartment 5, said spring holding the latch 16 nor-

mally in a lowered position in an opening 19 provided for the latch in the outer end of the casing 3.

Revolutionarily mounted in the partitions 8 and 9 and the bearing 10 is a shaft 20 that has the end thereof provided with a gear wheel 21 and a beveled gear wheel 22. The gear wheel 21 meshes with an elongated gear wheel 23 mounted upon a shaft 24, journaled in the partitions 7 and 9. The shaft 24 has one end thereof threaded to provide a screw 25 and said screw is adjustably mounted in an opening 26 provided therefor in the end wall 27 of the casing 3. The shaft 24, adjacent to the screw 25, has a transverse opening 28.

Meshing with the beveled gear wheel 22 are beveled gear wheels 29 loosely mounted upon a connecting spindle 30. The beveled gear wheels 29 have hubs 31 extending into bearings 32, carried by the inner sides of the casing. The hubs 31 terminate in rectangular shanks 33 within the bearings 32, and a key can be placed in engagement with the shanks 33 for rotating the beveled gear 35 wheels 29 and 22, and gear wheels 21 and 23, and the screw 25. In order that easy access can be had to one of the shanks 33, the door 1 and the face plate 12 have alining openings 34 registering with the bearing 32. 85

The door frame 35 is recessed, as at 36 to accommodate a strike plate 37, said plate having a slot 38 and a beveled lug 39, said slot receiving the latch 16. The strike plate has an opening 40 and the door frame 35 has a recess 41 in communication with said opening. The opening 40 and the recess 41 receive the screw 25. When the screw 25 is in a locked position, a screw 42 is inserted in an opening 43 provided therefor in the front plate 11, said screw entering the opening 28 of the shaft 24 and preventing the shaft from being rotated.

To operate the lock, the screw 42 is removed from engagement with the shaft 24, after which the key is inserted to engage with the spindle 30, the latter is rotated whereby the gears 29 are operated driving the gear wheel 21, the latter meshing with the gear wheel 23 will revolve the shaft or spindle 24 causing the threaded part 25 thereof to move inwardly and out of the opening 40. The knob 14 is then turned to release the latch 16, the door can then be swung open. 105 110

What I claim is:—

1. In a lock, the combination with a strike plate having an opening formed therein, and a casing, of a shaft rotatably mounted in said casing, a screw formed integral with said shaft and adjustably mounted in the end of said casing and adapted to extend into the opening of said strike plate, a gear wheel mounted upon said shaft, another shaft journaled in said casing, a gear wheel carried thereby and meshing with the first mentioned gear wheel, a beveled gear wheel carried by the first mentioned shaft, beveled gear wheels meshing with said beveled gear wheel and having hubs provided with shanks adapted to receive a key whereby said beveled gear wheels can be revolved to impart a rotary movement to said shafts and adjust the screw of the first mentioned shaft, and means extending into said casing and detachably connected to the first mentioned shaft to lock said shaft against rotation. 35
- 10 2. In a lock, the combination with a strike plate having an opening formed therein, and a casing, of a shaft rotatably mounted in said casing, a screw formed integral with said shaft and adjustably mounted in the end of said casing and adapted to extend into the opening of said strike plate, a gear wheel mounted upon said shaft, another shaft journaled in said casing, a gear wheel carried thereby and meshing with the first mentioned gear wheel, a beveled gear wheel carried by the first mentioned shaft, beveled gear wheels meshing with said beveled gear wheel and having hubs provided with shanks adapted to receive a key whereby said beveled gear wheels can be revolved to impart a rotary movement to said shafts and adjust the screw of the first mentioned shaft. 40
- 15 3. In a lock, the combination with a casing, of shafts revolvably mounted therein and adapted to rotate simultaneously, a screw carried by one of said shafts and extending through the end wall of said casing, beveled gear wheels revolvably supported by said casing and adapted when rotated to impart a movement to said shafts, 45 and means extending into said casing and engaging one of said shafts to lock both of said shafts against rotation. 50

In testimony whereof I affix my signature in the presence of two witnesses.

JÓZSEF JUHÁSZ.
